UNITED STATES PATENT OFFICE.

CHARLES B. GRACEY, OF CORAOPOLIS, PENNSYLVANIA, ASSIGNOR OF ONE-FOURTH TO
JAMES N. COOKE, OF PITTSBURGH, PENNSYLVANIA.

NUT-LOCK.

1,233,342.

Specification of Letters Patent. Patented July 17, 1917.

Application filed July 22, 1915. Serial No. 41,231.

To all whom it may concern:

Be it known that I, CHARLES B. GRACEY, a citizen of the United States, and a resident of Coraopolis, in the county of Allegheny and State of Pennsylvania, have invented a new and useful Improvement in Nut-Locks; and I do hereby declare the following to be a full, clear, and exact description thereof.

10 My invention relates to nut locks, and has special reference to the class of nut-locks in which a spring metal washer or locking plate is employed.

15 The object of my invention is to provide a cheap, simple and efficient nut-lock which can be used with the usual form of nut, and can also be used with the usual forms of fish-plate and nuts when applied to railroad rails.

20 To these ends my invention consists, generally stated, in the novel arrangement, construction and combination of parts, as hereinafter more specifically set forth and described and particularly pointed out in the 25 claims hereof.

To enable others skilled in the art to which my invention appertains to construct and use my improved nut-lock, I will describe the same more fully, referring to the 30 accompanying drawing, in which—

Figure 1 is a side elevation of a railroad rail joint having my improved nut-lock applied thereto;

Fig. 2 is a cross-section of the same on 35 the line 2—2 Fig. 1;

Fig. 3 is an enlarged face view of the locking plate;

Fig. 4 is a rear view of the same;

Fig. 5 is a cross-section of the plate on 40 the line 5—5 Fig. 3; and

Figs. 6, 7 and 8 are views of other forms of the plate.

Like symbols of reference herein indicate like parts in each of the figures of the drawing.

As illustrated in the drawing *a* represents the ordinary rail-road rail and *b* the usual fish-plates on the sides of the same, which are placed over the usual joints between the abutting ends of the rails and are held to such rails by screw bolts *c* and nuts *d* engaging therewith in the usual manner.

Between the fish-plate *b* and each of the nuts *d* is the washer or locking plate 1, which 55 is formed of any suitable spring metal such

as steel, and is provided with the aperture or hole 2' centrally of the same for placing the same around each of the bolts *c*. The locking plate 1 is of sufficient length to provide for the ends being turned inwardly so as to form the inclined wing portions 2 for biting or engaging the fish-plate *b* when in position, and extending inwardly and around the bolt hole 2' is the circular flange 3 for engaging such fish-plate when in position. This flange 3 is formed out of the locking plate 1 in any suitable manner, such as by drop forging or pressing the metal of the plate, and when so formed is concavo-convex in cross-section. The outer face on 70 the flat or intermediate portion 4 of the locking plate 1 is also provided with a socket 5 of the same shape as the periphery of nuts *d* for the reception of one of such nuts when in position, and in the formation of 75 such socket in the manner of drop forming or pressing, the metal in the plate will be also extended out on the inner face of such portion of the same at such socket, and around the flange 3, as shown at 6. 80

In the use of my improved nut-lock, after the fish-plates *b* are placed in position against the rails *a* and around the bolts *c* through the bolt holes 2' in such plates, a locking plate 1 is placed over each of the 85 bolts *c* through the bolt holes 2' in such plate, and upon each of the nuts *d* being placed on the screw ends *c* of such bolts and screwed down to place against the plate 1, the outer edge or face on the flange 3 will 90 engage the fish-plates and the edges on ends 2 of the plate will bite or engage the fish-plate *b*. When the nuts *d* are thus screwed up against the locking plate 1, they will each be seated in the socket 5 in the plate, and 95 by reason of such socket being of the same shape as the periphery of such nuts, the walls 6 forming such socket will prevent the nuts and bolts from turning.

As illustrated in the different figures of 100 the drawing hexagon nuts are shown, but it will be obvious that square, octagon and other shapes of nut can be used, and that one of the ends 2 on the locking plate 1 can be bent at right angles, as at 2" in Fig. 6, 105 for engaging the fish-plate *b*. If desired the walls of the socket 5 can also be rounded off as shown at 7, in Fig. 7, to more closely conform to the shape of the nuts *d*.

Various other modifications and changes 110

in the design, construction and application of my improved nut-lock, as well as the use of a separate washer *e* in place of the rear flange on the locking plate, as shown in Fig. 8, may be resorted to, without departing from the spirit of the invention, or sacrificing any of its advantages.

It will thus be seen that in the use of my improved nut-lock, the locking-plate employed will engage the fish-plate by the face of the circular flange, and will bite or engage the fish-plate by wings upon a further tightening up of the nuts, in case of any loosening up of the parts, and when the locking plate is in position a strong spring action will be had on the nuts by such plate at all times, so as to cause the threads of the nuts to bind upon the threads of the bolts, while any further tightening up of the nuts will cause the wings and flange on the locking plate to flatten out and engage or bite into the fish-plate, although a spring action will be had at all times by the locking contact with the nuts, thereby taking up loss by wear of bolts.

What I claim as my invention and desire to secure by Letters Patent is:

1. In a nut-lock the combination with a

bolt and nut, of a resilient plate having formed therein a relatively shallow socket conforming substantially in shape and size to the inner face and sides of the nut, the upper edges of said socket lying in substantially the same plane.

2. In a nut-lock, the combination with a bolt and a nut having a chamfered engaging face, of a resilient plate having formed therein a relatively shallow socket conforming substantially in shape and size to said chamfered engaging face and to the sides of the nut.

3. In a nut-lock, the combination with a bolt and a nut having a chamfered engaging face, of a resilient plate having formed therein a relatively shallow socket conforming substantially in shape and size to said chamfered engaging face and to the sides of the nut, the upper edges of said socket lying in substantially the same plane.

In testimony whereof, I, the said CHARLES B. GRACEY, have hereunto set my hand.

CHARLES B. GRACEY.
